UNITED STATES PATENT OFFICE.

JOHN F. CLEMENT, OF PHILADELPHIA, PENNSYLVANIA.

IMPACT-TOOL.

SPECIFICATION forming part of Letters Patent No. 364,481, dated June 7, 1887.

Application filed February 14, 1887. Serial No. 227,502. (No model.)

To all whom it may concern:

Be it known that I, JOHN F. CLEMENT, a citizen of the United States, residing in Philadelphia, Pennsylvania, have invented certain 55 Improvements in Dental Pluggers, of which the following is a specification.

My invention consists of certain improvements in impact-tools—such as tooth-pluggers, rock-drills, chipping or surfacing machines, &c.—the main objects of my improvements being to insure the rapid operation of the tool, and to provide a ready means of regulating the force of the blow.

In the accompanying drawings, Figure 1 is 15 a longitudinal sectional view of an impact-tool constructed in accordance with my invention. Fig. 2 is a sectional view of the pump for operating the same. Figs. 3 and 4 are views of parts of the tool, showing a controlling-valve 20 adjusted to different positions from that shown in Fig. 1. Fig. 5 is a transverse section of the lower portion of the device. Fig. 6 is a view illustrating a method of operating a pump for the tool shown in Fig. 1. Fig. 7 is a view of 25 a valve structure adapted for use in connection with the tool when the latter is operated by a single-action pump, and Fig. 8 is a view of another single-action tool with modified form of regulator.

30 In Fig. 1, A represents a cylinder containing a plunger or ram, B, which can move freely in said cylinder. The lower end of the cylinder is closed by a tubular plug, a, in which is guided and free to slide a stem, D, the upper end of which projects into the cylinder, and has a flange or collar, b, forming a bearing for a spring, d, which is contained partly in a recess in the inner end of the plug a, and tends to elevate the stem D to an extent permitted 35 by the head of a stop-screw, f, the stem of the latter passing through an opening in the flange b, and having a thread adapted to an internal thread in an opening in the inner end of the plug a, so that by a proper adjustment of the 40 screw the extent of inward movement or lift of the stem D, due to the action of the spring d, can be readily regulated.

In the bottom of the spring-receiving recess of the plug a is a washer, i, of rubber or like 45 material, fitting snugly to the stem D, so as to prevent leakage around the same.

The tool F is secured to the stem D by means

of a transverse key, g, adapted to recesses in the tool and stem, the opposite projecting ends of this key being adapted to vertical slots h in the plug a, so that longitudinal movement of the stem, and of the tool carried thereby, is always permitted, and ready access can be had to the retaining-key at any time, rapid changing of the tools being thus rendered possible. 60

With the lower end of the cylinder A communicates a pipe, m, a similar pipe, n, communicating with the upper end of the cylinder, and these pipes communicate, through flexible tubes p, with pipes n' m', respectively at the 65 upper and lower ends of a pump-cylinder, J, which contains a piston, J', the rod k of which is reciprocated in any suitable manner.

On the upward stroke of the piston air is forced from the upper portion of the pump-cylinder into the upper portion of the cylinder A, and drawn from the lower end of the latter into the lower portion of the pump-cylinder, thus causing the downward movement of the plunger or ram B, which strikes a blow upon 75 the inner end of the stem D and drives the latter forcibly downward. On the downward stroke of the pump-piston the action is reversed, air being forced into the lower end of the cylinder A and drawn from the upper end 80 of the same, so as to cause the elevation of the ram B, the stem D being lifted by its spring d to the extent permitted by the stop-screw f.

In order to prevent the ram in its upward movement from coming into forcible contact 85 with the head a' at the upper end of the cylinder A, a light spring, s, is interposed between said head and the ram, as shown. The movement of the ram B is thus due both to the direct impulse of the blast of air on one side 90 and the withdrawal of the air from the opposite side, so that a forcible blow is delivered by the ram. In order, however, that the force of the blow may be regulated during the operation of the tool, as may be required by the 95 character of the work which is being performed, I connect the pipes m and n by means of a transverse valve-chest, K, in which is a sliding valve, M, having two ports, t and t', the former passing directly through the valve, 100 but the port t' being right-angled and extending to the end of the valve. When, therefore, the valve M is adjusted to the position shown in Fig. 1, the flow of air to or from the upper

end of the cylinder A is cut off and a direct communication is established between the two pipes *m* and *n*, so that air flows directly from one to the other, and no influence is exerted 5 upon the ram B.

When the valve is adjusted to the position shown in Fig. 3, there is a restricted communication between the pipes *m* and *n*, and a restricted communication between the pipe *n* 10 and the upper end of the cylinder A, so that the ram is subjected to but a portion of the full force of the blast, while, when the valve is adjusted to the position shown in Fig. 4, direct communication between the pipes *m* and 15 *n* is cut off and free communication opened between the pipe *n* and the upper end of the cylinder A, so that the ram acts with full force.

The valve M has a projecting stem, which is depressed in order to operate the valve, a 20 spring, *v*, serving to move the valve outward.

The valve-stem may be under the influence of an arm, *w*, at the side of the cylinder, as shown, for instance, by dotted lines in Fig. 1, so as to provide for the ready operation of the 25 valve from any point in the length of the cylinder.

The form of valve described may be used with advantage in connection with a tool operated by a single-acting pump, in which case 30 but a single air-pipe is used, one end of the valve-chest being open to the atmosphere, as shown in Fig. 7.

Other means within the scope of my invention may be used for regulating the force of 35 the blow in a single-acting tool. For instance, in Fig. 8 I have shown a construction in which a simple branch tube, *c*, communicates with the blast-pipe at a point between the pump and the ram-cylinder, this tube having a series 40 of orifices, *c'*, which may be covered by the fingers of the hand in which the tool is held, the area of opening for the inlet of air to or 45 its discharge from the branch pipe being regulated by moving the fingers so as to uncover one or more of the orifices; or the pipe may, if desired, be open at the end, and may be elastic, so that it can be compressed to a greater or less extent by the finger, as may be suggested by the desired regulation of area of the 50 passage provided by the pipe.

The pump shown in this apparatus is a cylinder with a diaphragm, *V*, instead of a piston, this form being preferred for use in connection with a single-acting tool.

55 Prior to my invention pneumatic pluggers have been devised in which the force of the blow delivered by the ram is regulated by restricting the inlet of air to or its discharge from the cylinder below the ram, or by restricting the flow through the blast-pipe; but both of these plans are objectionable, on account of the back-pressure or drag upon the pump, which results from such restriction. My invention differs from these in effecting 60 the regulation, by providing the blast-pipe with means for supplying said pipe with air, or for the escape of air from said pipe at a

point between the pump and the ram cylinder. This independent supply and discharge is in the nature of a leak in the blast-pipe, and hence weakens the force of the blast or partial vacuum to the extent of the volume of said leak. 70

Although in the case of the double-action tool there is a partial obstruction of the communication between the blast-pipe and the cylinder, this is always counteracted by the provision of an independent means of supply and discharge equal to the obstruction in the regular communication, so that there is never 80 any back-pressure or drag to interfere with the perfect freedom and uniformity of movement of the pump, or with the free reciprocation of the ram in its cylinder. 75

I can use the ordinary form of dental engine 85 for operating either the double-acting pump shown in Fig. 1 or the single-acting pump shown in Fig. 8 when my improved impact-tool is to be used as a dental plunger. In this case I bolt the standard carrying the pump 90 directly to the vertical post or column *P* of the dental engine, the driving-shaft *u* of the pump having a pulley for receiving, as shown by dotted lines in Fig. 8, the belt *x* from the drive-wheel *S*, which is operated by the treadle. 95 Said shaft *u* is also provided with a crank-disk, *y*, a rod from which is connected either to the diaphragm *V* of the single-acting pump or to the piston-rod *k* of the pump when the latter is double-acting. 100

In order that I may use for the purpose of driving the pump the same belt *x* which is used for driving the ordinary tool-operating shaft, *T*, of the dental engine, I provide said belt with a detachable section, *x'*, the removal 105 of which shortens the belt to the extent necessary to adapt it for driving the pump-operating shaft *u*, which is somewhat below the shaft *T*, ordinary hook-and-eye couplings being used to connect the ends of the belt *x* to the ends of the section *x'*, or for connecting the ends of said belt *x* together when the section *x'* is removed. 110

I am aware that a pneumatic plunger has been devised in which the pump was operated 115 by direct connection with the drive-wheel *S* of a dental engine; but with such a device but a few blows per minute can be given to the tool, whereas when the parts are constructed in accordance with my invention hundreds or 120 thousands of blows per minute can be given.

I claim as my invention—

1. The combination, in an impact-tool, of the ram-cylinder and its ram, a pump, and a pipe connecting said pump to the ram-cylinder, said 125 pipe having between the pump and the ram-cylinder a passage through which air can enter or leave the pipe, all substantially as specified.

2. The combination, in an impact-tool, of the 130 ram-cylinder and its ram, a pump, a pipe connecting the pump and cylinder, and having between the two a passage through which air can enter or leave the pipe, and means for regulating

ing the effective inlet or discharge area of said passage, all substantially as specified.

3. The combination, in an impact-tool, of the ram-cylinder and ram, a double-acting pump, 5 and pipes whereby communication is afforded between the opposite ends of the pump and corresponding ends of the ram-cylinder, all substantially as specified.

4. The combination of the cylinder and its 10 ram, the movable stem and its lifting-spring, and a stop-screw independent of said spring and adjustable in a direction parallel with the line of movement of the stem, so as to limit the lift of said stem by the spring, all substantially as 15 specified.

5. The combination of the ram-cylinder and ram, a pump, a pipe connecting the pump and ram-cylinder, and a valve having two ports, one providing a direct communication between 20 the pipe and cylinder and the other serving to divert the current, all substantially as specified.

6. The combination of the ram-cylinder and its ram, the pump, the two pipes, one communicating with one end of the cylinder and 25 pump and the other with the opposite ends thereof, a valve-chest connecting the two pipes, and a valve having two ports, one forming a di-

rect communication between one of the pipes and the cylinder and the other providing a direct communication between the two pipes, all 30 substantially as specified.

7. The combination of a dental engine, the ram-cylinder and its ram, the pump, and a connecting-pipe, a pump-carrier mounted on the post of the dental engine, a pump-operating 35 counter-shaft, and a belt whereby said shaft is operated from the drive-wheel of the engine, all substantially as specified.

8. The combination of a dental engine, its 40 drive-wheel and tool-operating shaft, a pump structure mounted on the standard of the engine, and a driving-belt having a detachable section, whereby it can be used either for driving the tool-operating shaft of the engine or the operating-shaft of the pump, all substantially 45 as specified.

In testimony whereof I have signed my name to this specification in the presence of two subscribing witnesses.

JOHN F. CLEMENT.
